WILLIAM PARKIN, OF TAUNTON, MASSACHUSETTS, ASSIGNOR TO
REED AND BARTON, OF SAME PLACE.

Design No. 3,340, dated January 12, 1869.

DESIGN FOR A BUTTER-VASE, OR COOLER.

The Schedule referred to in these Letters Patent and making part of the same.

To all persons to whom these presents may come:

Be it known that I, WILLIAM PARKIN, of Taunton, in the county of Bristol, and State of Massachusetts, have invented or produced "a new and ornamental Design for a Butter-Vase, or Cooler;" and I do hereby declare the same to be represented in the accompanying drawing, and thus described, the said drawing being a perspective elevation of it.

The drawing shows the bowl A and the cover B.

The design has particular reference to the bowl and its legs C, each of the latter of which is exhibited as bracketed or formed with a projection or shelf, a, to support a statuette or figure of a warrior.

The bowl has two handles, D D, and a milled flange, b.

It also has a convex bottom, c, provided with the bracketed legs C.

The cover, bell-shaped or formed as represented, is surmounted by the statuette of a cow.

The ornamentation of the surface of the cover, that is, the fence and trees shown thereon, forms no part of the design.

I claim as my invention—

The ornamental design of the bowl and its bracketed legs, and also that of the cover, the whole being as represented in the accompanying drawing.

WM. PARKIN.
